UNITED STATES PATENT OFFICE.

CHARLES W. HAWTIN, OF LONDON, ENGLAND, ASSIGNOR OF ONE-HALF TO WILLIAM GEORGE MASON, OF LONDON, W. 1, ENGLAND.

SHAVING BRUSH.

Application filed October 30, 1922. Serial No. 597,392.

To all whom it may concern:

Be it known that I, CHARLES WILLIAM HAWTIN, a subject of the King of Great Britain and Ireland, residing at 71 Rusthall 5 Avenue, Bedford Park, London, W. 4, England, have invented new and useful Improvements in Shaving Brushes (on which application has been made for Letters Patent in Great Britain, No. 26593, filed 8th 10 October, 1921), of which the following is a specification.

The present invention relates to improvements in shaving brushes.

The present invention comprises a brush 15 handle in which one or more open tubes are provided in that portion of the brush material within the brush socket leading from the hollow interior of the brush handle to the brushing portion of the brush and in 20 which the hollow portion of the handle is perforated, said tube or tubes and perforations providing for a free circulation of air through the central portion of the brushing material, thus drying the brush and keeping 25 it in a hygienic condition.

The invention is illustrated by way of example in the accompanying drawings, in which—

Figure 1 shows the brush forming the 30 present invention.

Figure 2 shows the brush with the socket part in section, and

Figures 3 and 4 show detailed views of alternative forms of inner tubes which are 35 adapted to ventilate the central portion of the brush material as well as to wedge or grip the brush in the handle socket.

Referring now to the drawings, the brush material 1 is adapted to be placed in the brush socket 2 of the handle around a conical tubular core 3. This tube is hollow.

It will be readily understood that when the tube is placed firmly in position that portion of the brush material within the 45 socket is securely gripped between the said tube and the wall of the socket, and secured thereby in addition to the ordinary methods used for this purpose, such as for instance, the cement indicated at 7.

Owing to the fact that the core 3 is hollow and to the fact that air holes 4 are provided in screw-on cap 5 of the brush handle, a free circulation of air is obtained through the central portion of the brushing material thus drying the brush and keeping it in 50 55 a hygienic condition.

In order to increase the circulation of air perforations 6 may be provided in the tube 3' as shown in Figure 4.

What I claim is:—

1. A shaving brush, comprising a hollow handle provided at one end with a socket and having perforations in the walls thereof, brush material mounted in said socket, a tubular member mounted in that portion 65 of the brush material located within the brush socket, the bore of said member cooperating with the perforations in said hollow handle to permit a free circulation of air through the central portion of the brush material. 70

2. A shaving brush, comprising a hollow handle provided at one end with a socket, brush material mounted in said socket, a cap 75 detachably secured to the end of said handle opposite to said socket and provided with perforations in its walls, and an open tubular member mounted in that portion of the brush material within the socket, the bore of said member cooperating with said perforations in the cap to provide a free circulation of air through the central portion of the brush material.

3. A shaving brush, comprising a hollow handle provided at one end with a tuft-receiving socket communicating with the interior thereof, bristles mounted in the socket, and a tubular core within the socket and surrounded by the butt-ends of the bristles forming said tuft, said core terminating in 85 90 the bristle tuft at substantially the base portion thereof, said handle being provided with perforations whereby air may circulate through the bristles.

In witness whereof I have signed my name 95 to this specification.

C. W. HAWTIN.
